United States Patent Office.

JEREMIAH BARNEY, OF PERRY'S MILLS, NEW YORK.

Letters Patent No. 92,510, dated July 13, 1869.

IMPROVEMENT IN TURBINE WATER-WHEELS.

The Schedule referred to in these Letters Patent and making part of the same.

To all whom it may concern:

Be it known that I, JEREMIAH BARNEY, of Perry's Mills, in the county of Clinton, and State of New York, have invented a new and improved Water-Wheel; and I do hereby declare that the following is a full, clear, and exact description thereof, which will enable others skilled in the art to make and use the same, reference being had to the accompanying drawings, forming part of this specification, in which--

Figure 1 is a vertical section of my improved wheel.

Figure 2 is a detail sectional view of the same, taken through the line xx , fig. 1.

Similar letters of reference indicate like parts.

My invention has for its object to furnish an improved water-wheel, which shall be so constructed as to utilize both the head and weight of the water, for the propulsion of the wheel, to a greater extent than is possible with water-wheels constructed in the ordinary manner; and

It consists in the construction and combination of the various parts of the wheel as hereinafter more fully described.

A is the shaft, to which the drum or wheel B is securely attached.

The upper head of the drum or wheel B projects beyond the buckets, as shown in fig. 1.

The lower part of the wheel B is encased with a casing, C, which is connected with the lower end of the shaft A and of the wheel B, so as to revolve with, and be a part of the said wheel.

The upper edge of the casing C is provided with a flange, projecting outward, so that its outer edge may be even with the outer edge of the upper end or head of the wheel B, thus forming a circular channel around the upper part of the said wheel, through which the water may be introduced to the buckets D.

The upper parts of the buckets D are made vertical, and project further than their lower parts, so as to enter the channel between the projecting edge of the head of the wheel B and the projecting flange of the casing C, as shown in fig. 1.

The lower parts of the buckets D descend spirally along the face of the drum or wheel B, being inclined

toward the direction from which the water flows into the wheel.

E is the spout or flume, through which the water flows to the buckets D, through the space between the head of the wheel B and the flange of the casing C.

The spout E is so arranged that the water, as it flows from said spout, may strike squarely against the upper or vertical parts of the buckets D, so as to utilize the entire projectile force or head of the water.

As the projectile force of the water diminishes, it gradually yields to the attraction of gravity, and, as the resultant of these two forces, it acts upon the inclined or spiral parts of the bucket D, as it descends along said buckets, thus utilizing both the projectile force and the weight of the water for the propulsion of the wheel.

F is a stationary casing, attached to and supported by the end of the spout E, and which passes around the outer projecting-edge of the upper head of the wheel B, and around the outer projecting-edge of the flange of the casing C, so as to entirely enclose the channel or space through which the upper parts of the buckets D move, and through which the water is introduced to the said buckets, entirely preventing the escape of the water through the upper part of the wheel.

Having thus described my invention,

I claim as new, and desire to secure by Letters Patent—

1. The buckets D, constructed as described, with their upper portions vertical, and their lower portions extending spirally downward, the former projecting beyond the latter, and all arranged and operating as described, for the purpose specified.

2. An improved water-wheel, formed by the combination of the wheel B, casing C, provided with an outwardly-projecting flange upon its upper edge, buckets D, spout E, and stationary casing F, with each other, substantially as herein shown and described, and for the purpose set forth.

JEREMIAH BARNEY.
